United States Patent Office.

CHARLES PARKER AND WILLIAM VOGLER, OF CANTERBURY, NEW HAMPSHIRE.

Letters Patent No. 69,364, dated October 1, 1867.

IMPROVEMENT IN CARRIAGE-STEPS.

The Schedule referred to in these Letters Patent and making part of the same.

TO ALL WHOM IT MAY CONCERN:

Be it known that we, CHARLES PARKER and WILLIAM VOGLER, of Canterbury, in the county of Merrimack, and State of New Hampshire, have invented a new and improved Arrangement of Carriage-Steps; and we do hereby declare that the following is a full and exact description thereof, reference being had to the accompanying drawings making a part of this specification, and to the letters of reference marked thereon.

This invention consists in communicating to the steps of a carriage such a motion as insures their non-interference with the forward wheels when either of the latter approaches or comes in contact with the side of the carriage during the operation of turning.

To enable those skilled in the art to make and use our invention, we will now proceed to describe its construction and operation.

A represents the bottom of a riding-buggy. *a* represents the steps thereof, attached as usual at the sides between the forward and rear wheels in a position to facilitate entering the carriage. The steps are attached by pivots at *p* to the framework, and are provided with fan-shaped arms *d*, extending under the bottom of the carriage, the function of which is to distribute the strain brought upon the step by the weight of the person entering the carriage over so large a space that no individual part of the portion enduring the strain shall be injuriously affected thereby. To one side of each of the said fan-shaped projections are jointed at *e* the ends of connecting-rods *b*, the other ends of which are jointed to the outer ends of levers *c*, the inner ends of which are united by rods *b'* to eyes *f*, on the forward axle, at equal distances from the centre thereof.

Now, suppose the carriage to be turning to the left. During the operation the left connecting-rod *b'*, receiving motion from the axle, forces the inner end of the left lever *c* backward. The consequent forward motion of the outer end of the left lever thrusts toward the front the left connecting-rod *b* and the left fan-shaped arm *d*. As the latter is pivoted at *p*, the step *a*, on the opposite of the pivot, is moved toward the rear and right, and thus kept out of the way of the wheel. At the same time the right connecting-rod *b'*, also receiving motion from the axle, draws the inner end of the right lever *c* forward. The consequent backward motion of the outer end of the right lever draws toward the rear the right connecting-rod *b* and the right fan-shaped arm *d*. As the latter is also pivoted at *p*, the step *a*, on the opposite side of the pivot, is moved toward the front and left, and thus brought into a convenient position to receive the foot of the person getting into the carriage.

When the carriage is turning to the right the operations above described are reversed.

It will thus be perceived that, in whatever direction the carriage may be turned, one of the steps is gotten out of the way to prevent inconvenience, and the other brought in the way for the sake of convenience. Two steps or more can be used upon each side, if desired.

What we claim, and desire to secure by Letters Patent, is—

1. A vibrating carriage-step, operated by mechanism connected with the forward axle, substantially as described.
2. The vibrating step *a*, in combination with the fan-shaped arm *d*, levers *b b'*, and cross-bar *c*, substantially as described.
3. The step *a*, provided with fan-shaped arm *d*, substantially as described.

CHARLES PARKER,
WILLIAM VOGLER.
